UNITED STATES PATENT OFFICE.

JUDSON HAYWARD, OF TEANECK, NEW JERSEY.

BUCKET.

1,232,542.

Specification of Letters Patent. Patented July 10, 1917.

Application filed July 15, 1911. Serial No. 638,662.

To all whom it may concern:

Be it known that I, JUDSON HAYWARD, a citizen of the United States, residing at Teaneck, in the county of Bergen and State of New Jersey, have invented certain new and useful Improvements in Buckets, of which the following is a full, clear, and exact specification, such as will enable others skilled in the art to which it appertains to 10 make and use the same.

This invention relates to excavating apparatus and has for its object to provide certain improvements in buckets employed for conveying, dredging and excavating.

15 Heretofore it has been customary to employ in connection with an orange peel or clam shell bucket two operating lines, one for hoisting and holding the bucket and the other for closing the bucket, the bucket 20 being opened by slackening off on the closing line, when the weight of the material and of the interior mechanism of the bucket is sufficient to cause the bucket to open by gravity and drop the load.

25 In buckets so constructed, operated by two lines, two drums are of course necessary, one for reeling and unreeling the hoisting line and the other for reeling and unreeling the closing line.

30 One of the objects of my invention is to provide a bucket for conveying, dredging and excavating, employing only a single line, said line acting to close the bucket as well as to hoist and hold the same in position to drop the load.

35 A further object of my invention is to provide a self-contained means on a bucket, acting in conjunction with the closing and hoisting line to open the bucket.

40 A further object of my invention is to dispense with one of the drums, as well as one of the lines heretofore used in the operation of such buckets.

45 Further objects, such as economy of installation, economy in cost of materials and labor, and simplicity of operation of buckets constructed and operated according to my invention, will be readily apparent from the following description in connection with 50 the accompanying drawings, in which,—

Figure 1 is a side elevation showing the bucket and a steam power plant for operating the same;

Fig. 2 is a side elevation of the bucket;

Fig. 3 is an end elevation of the same; 55

Fig. 4 is a side elevation partly broken away, showing a modification of the invention;

Fig. 5 is an end view of the same;

Fig. 6 is a side elevation showing another 60 modification of the invention;

Fig. 7 is an end view thereof; and

Fig. 8 is an enlarged detail of a portion of the apparatus shown in Fig. 1.

Referring to the construction illustrated, 65

A represents a platform upon which is mounted a pivoted swinging derrick which may follow any of the well known forms of construction and operation and requires no detailed description, it being sufficient to 70

state that B indicates the mast and C the boom, which will be suitably supported, one of the guy cables being shown at E. Upon the platform A is mounted an engine, indicated in whole at F, for driving the hoisting drum 75

G, to which is secured the closing and hoisting line H, which latter passes over a sheave H', mounted upon the mast B, and thence over a sheave H² suspended from the boom 80

C. The closing and hoisting line H, in my preferred form is divided at its outer end, to form two branches I, I'. The bucket proper is also of old and well known construction and needs no detailed description

except the statement that it consists of the 85 bowl sections J, J', the side arms K, K' which are pivotally connected by the power shaft L, upon which is mounted the power

wheel M having a hub portion M'. It also 90 comprises the connecting links N, N' which are pivotally connected to the bowl sections J, J' and also pivotally secured to the supporting head or block O, by means of the

pintle O', from which pintle are suspended 95 a pair of operating chains P, P', the latter at their opposite ends being connected to

and adapted to be wound about the power 100 wheel hub M', and, through the rotation of the power wheel, to close and open the bucket. It will be seen that when the power

wheel is rotated in one direction the operating chains P, P' wind about the hub M' to lift the same and close the bucket, and when the power wheel is permitted to rotate in the 105 opposite direction, said chains will unwind and the power wheel and shaft be lowered by gravity to open the bucket.

Mounted upon the head block O of the

bucket, I provide a bearing block Q, comprising the base Q', and the side members Q². Upon one side of the said bearing block, and supported by the side members Q² is an 5 idler pulley R, over which passes the branch line I, one end of which is connected to the power wheel M. Upon the opposite side of the bearing block Q is mounted a motor S, whose armature shaft S' has its bearings in 10 the side members Q². Upon the shaft S' is also mounted a winding drum S², to which is secured the branch line I'. The operating wires T, T' pass from the motor over the idler pulley T² suspended from the boom C, 15 and thence to a take-up device T³ rotatably mounted upon the mast B. Said take-up device, as more clearly shown in Fig. 8, comprises a shaft T⁴, having its bearings in side supports T⁵, T⁶, rigidly connected to the 20 mast B. Upon said shaft is loosely mounted the winding drum T⁷, to which is connected one end of the conductors T, T', said conductors having electrical connection with annular conductor rings T⁸, T⁹, which are 25 suitably insulated and mounted upon the annular flange T¹⁰ and rotated therewith. Mounted upon and preferably formed integral with the winding drum T⁷ is a counterweight pulley member T¹¹, to which is secured one end of a rope T¹², to the other end of which is secured a counterweight T¹³, the 30 function of which counterweight is to take up any slack in the wires T, T', when the bucket is hoisted. 35 Rigidly mounted upon the support T⁵ are a plurality of conducting brushes T¹⁴, T¹⁵, which also are suitably insulated and are adapted to contact with the rotary electrical conductors T⁸, T⁹. To the conducting 40 brushes T¹⁴, T¹⁵ are connected wires T¹⁶, T¹⁷, which pass down the mast B and are at their lower ends connected to a controller U, of any well known form, mounted upon the platform A within convenient reach of the 45 engineer or operator.

The operation of the apparatus above described and as shown in Figs. 1, 2, 3 and 8 is as follows:

Assuming that the bucket is in closed position, with the power wheel elevated and operating chains wound, as shown in Figs. 50 2 and 3, the bucket carrying its load in position to drop the same, and the current off the motor, the operator turns on the current 55 through the controller U, the motor is started, which through the shaft S' operates the drum S² winding thereon the branch line I', dividing the weight carried by the branch line I and supporting the head of the bucket 60 upon said branch line I', lifting the same relative to the power wheel and load and as it is lifted, the operating chains P, P' unwind, the power wheel M is rotated and by the change of relative positions of the head 65 and power wheel the bowl sections open.

In the rotation of the power wheel the branch I is wound thereon. The operation is continued until the power wheel and bucket sections assume the position shown in dotted lines in Fig. 2.

The bucket, having opened, is ready for a new load and is dropped in open position onto the material to be moved. The current is now turned off from the motor. In closing the bucket, the line H is tightened, by 70 means of the hoisting drum G, and the bucket is thereby closed and hoisted and moved to the unloading point, where the operation above described is repeated. It will be clear that in closing the bucket, the branch 75 I' will be paid out to a limited extent, the shaft S', of course, running loose, with no current on the motor, in the closing operation. In the operation of lifting and lowering the bucket the slack in the conducting 80 wires T, T' is taken up and the wires paid out by the take-up device T³, which is actuated by the counterweight T¹³.

In the modifications illustrated in Figs. 4, 5, 6 and 7 the construction is designed to 90 obviate the necessity of using two branches on the closing and hoisting line. As shown in Figs. 4 and 5, a single line, indicated at 1, is provided, passing through the fair-leader indicated at 1¹, thence around a drum 95 indicated at 2, fast to the motor armature shaft 3 of the motor 3^a, mounted upon the bearing block 4. After passing about said drum the line 1 is secured to the power wheel 5. The operation in this instance is similar 100 to that above described, except that when the motor is actuated and the head of the bucket elevated by the drum 2 taking up the line 1, the line is paid out to the power wheel, thereby permitting the opening of 105 the bucket sections by gravity.

Referring to the construction illustrated in Figs. 6 and 7, I provide a sprocket wheel 15 mounted on the bearing block 16, which sprocket wheel is fast to the armature shaft 17 of the motor 18. The hoisting and closing line 19 is connected to a sprocket chain 20, passing through the fair-leader 21, and meshing with the teeth of the sprocket wheel 15, the lower end of said chain being connected to the power wheel 22. The operation of the construction shown in Figs. 6 and 7 is very similar to the operation of that shown in Figs. 4 and 5, except that as the motor 18 is rotated the sprocket wheel 115 20 positively engages the sprocket chain 20, and as the head of the bucket is elevated, the lower end of the sprocket chain is paid out permitting the bowl sections to open as before fully described.

I wish it to be understood that I do not confine myself to the precise details of construction and arrangement herein set forth, as modification and variation may be made without departing from the spirit of the in- 125 130

vention, as defined by the appended claims. Furthermore, my improvement may be applied to other forms of bucket than the one herein illustrated to show the application and operation of my invention.

5 What I claim is:

1. In a bucket, the combination of a plurality of bowl sections, a supporting head, bowl-closing mechanism connected to said head, a line connected to said mechanism for closing the bowl sections and hoisting the bucket, and a self-contained motor on said bucket connected to said line adapted only to open the bowl sections.
- 10 2. In a bucket, the combination of a plurality of bowl sections, a supporting head therefor, bowl-operating mechanism below the head movable from the head to open the bowl sections, flexible means connected to a hoisting drum and to said mechanism for closing said sections and for hoisting the bucket, and independently actuated power devices on said head engaging said flexible means to lift said head thereby opening the bowl sections.
- 15 3. The combination with a bucket comprising a supporting head, a plurality of bowl sections, power mechanism below the head adapted to open said bowl sections by gravity, flexible means connected to a hoisting drum and to said power mechanism for closing said bowl sections and for hoisting the bucket, and independently actuated devices upon said head for lifting the same, thereby opening said sections.
- 20 4. In a bucket, the combination of a plurality of bowl sections, a supporting head, a power wheel, flexible means coöperating with the power wheel to close the bowl sections and adapted to support and hoist the load, and mechanism on the head engaging said flexible means, for raising said head relatively to the power wheel to open the bowl sections.
- 25 5. In a bucket, the combination of a plurality of bowl sections, a supporting head, a power wheel, a line connected to a hoisting drum and to said power wheel to close the bowl sections and support and hoist the load, and means on said head acting on said line for lifting the head to open the bowl sections.
- 30 6. In a bucket, the combination of a plurality of bowl sections, a supporting head, a power wheel, a line connected to the power wheel to close the bowl sections and support and hoist the load, and means coöperating with said line but independently actuated, to change the position of the supporting head relatively to the power wheel, and thereby open the bowl sections.

- 35 7. In a bucket, the combination of a plurality of bowl sections, a supporting head for said bowl sections, a power wheel, a closing and hoisting line coöperating with

the power wheel to close the bowl sections and support the load, a motor on the supporting head and mechanism connected thereto and also connected to said line for supporting said head and raising the same relative to the power wheel to open the bowl sections.

8. In a bucket of the class described, the combination of a plurality of bowl sections, a supporting head connected to the bowl sections, a power wheel, a closing and hoisting line having branches, one of said branches being connected to the power wheel to close the bowl sections, and mechanism on said supporting head adapted to engage another branch of said line to raise the supporting head relative to the power wheel and thereby open the bowl sections, and means for actuating said line engaging mechanism.

9. In a bucket, the combination of a plurality of bowl sections, a supporting head pivotally connected to the bowl sections, a power wheel movable relative to said head and adapted by said movement to close and open the bowl sections, a line for actuating said power wheel and for hoisting the bucket, and means connected to said line for supporting and raising the supporting head relative to the power wheel.

10. A one-line bucket embodying relatively movable bucket members, a single line for hoisting and closing said bucket members, and motor operated means independent of the action of said single line in closing the bucket, said motor operated means acting primarily for opening said bucket members.

11. A one-line bucket embodying relatively movable bucket members, a single line for hoisting and closing said bucket, and motor operated means acting independently of the closing action of said line, said motor operated means including a motor the power of which is applied rotatively to positively open but not close the bucket members.

12. A one-line bucket embodying pivoted bucket members, a single line, means operable by said line for hoisting and closing said bucket members, and motor operated mechanism independent of the closing action of the closing means for effecting the positive opening of said bucket members.

13. A one-line bucket embodying a sectional bucket structure closing means, including a single line for hoisting and closing the bucket structure, and motor operated means unitary with the bucket structure and operable independently of the operation of the closing means for positively opening said bucket structure.

14. A one-line bucket embodying a sectional bucket structure closing means, including a single line for hoisting and closing said bucket structure, an electric motor unitary with the bucket structure, and

bucket opening means operated by said electric motor, said bucket opening means and motor having no part in closing the bucket.

15. A one-line bucket embodying a sectional bucket structure, a single line, means actuated by stress on the line for closing the bucket structure, a motor carried on the bucket structure, and bucket opening means operable by said motor, said bucket 10 opening means and the motor being operable independently of the closing action of said single line and the bucket closing means.

16. A one-line bucket embodying a sectional bucket structure, a single line, bucket

closing means operable by stress on the line 15 for closing the bucket structure, a motor carried on the bucket structure, bucket opening means operable by said motor for positively opening the bucket structure independently of the operation of the line and 20 of the bucket closing means, and means for supplying energy to said motor in all positions of the bucket.

JUDSON HAYWARD.
